UNITED STATES PATENT OFFICE

2,117,508

ELECTRICALLY DRIVEN MASTER CLOCK

Ferdinand Schneider, Fulda, Germany

Application December 28, 1935, Serial No. 56,459

2 Claims. (Cl. 200—30)

This invention relates to electrically driven master clocks, which serve for the electrical control of secondary clocks. The contact device for closing the operating circuit for the electric motor for driving the master-clock as well as the contact-device for reversing the operating current form the subject matter of separate applications for U. S. patent Ser. #56,458 and 56,457 filed by me Dec. 28, 1935, simultaneously with this application.

According to the present invention a small weighted lever is lifted and dropped every minute by the driving work of the master-clock, the weight of said lever amounting to about 1 gram. Thus only an extremely small resistance will have to be overcome by the driving work of the master-clock in order to release the control-mechanism for the secondary clocks. As said resistance is represented by a constant small weight which may easily be released by the driving-work of the master-clock, the latter may be regulated to keep time with the greatest degree of precision. In heretofore known master-clocks the releasing of the contacts is effected as a rule every minute by means of the second-wheel of the clock, the contact being made in many cases by means of contact-disks, contact-pins or the like mounted on the axle of the second-wheel. Contact and release devices of this kind, however, will necessarily unfavorably affect the driving organs of the clock-work and, therefore, must be made of very small weight preventing said devices to be made in the form of a sufficiently solid and rugged mechanism able to reliably serve its purpose. A further disadvantage of known contact and release devices of this kind consists therein, that a minute-release cannot immediately be used without difficulties with all kinds of clocks, such as second-clocks with second-pendulums, three-quarter second-pendulums, half-second pendulums, quarter-second pendulums or finally with works using balance-wheels. It had, therefore, been impossible to use one and the same contact and release organ with different kinds of clockworks.

By my present invention the minute-release is effected by the usual wheels which serve for driving the hands of the clock, and more particularly by means of the aforementioned contact and release device which is of rugged and reliable construction. The release-wheels, moreover, are in every case meshing with the driving-wheel for the minute-hand of the clock, said wheel being mounted on the axle of the minute-wheel of the clockwork. The same wheel-system for the hands

may, therefore, immediately be used with second, three-quarter second, half-second or quarter-second pendulum-operated clockworks as well as with works that are operated by a balance-wheel. As the wheel for the minute-hand is mounted on the shaft to which the driving spring is connected, the latter may be so chosen that an undiminished driving power is always supplied to the driving-wheels of the clockwork. The swing of the pendulum will thus always be maintained at a constant amplitude, with the result that even with half-second-pendulum-operated clocks the time-keeping qualities will be of the highest order. Moreover, by using a contact-device of rugged and reliable construction, there will be attained an absolutely reliable operation of the system. In my present master-clock, furthermore, the driving spring of the clockwork is rewound every minute simultaneously with the revolution of the contact-wheels by means of winding-wheels meshing with the driving-wheels, so that practically always a constant driving power is supplied to the driving-mechanism of the clock. According to my invention, furthermore, the contact-disk is in mesh with the motor-operated wheels of the clockwork and thus rotated simultaneously with said wheels, while the ratio of gearing between the latter and the motor is rather high with the result that a relatively large contact-pressure and a reliable electrical contact is obtainable at the contact-member of the contact-disk. In consequence of this, said contact-member will be able to operate powerful lever-switches serving to furnish the alternating current-impulses for the control of the secondary clocks. This contact-device forms the subject-matter of a separate application for U. S. patent Ser. #56,458 filed by me simultaneously with this application.

Owing to the combination of the aforementioned arrangements the master-clock will be able to reliably operate a great number of secondary clocks connected up in a loop with said master-clock, in a manner to attain greatest reliability and safety of operation of the system and more particularly also in case a master-clock of the smallest type is used, for instance a quarter-second pendulum-operated clock. The small electric motor will be rotated every minute for a period of about two seconds, figured from the moment at which the motor is started to the moment at which the motor comes to standstill in no-load condition. The small electric motor which is preferably used in connection with the present system of master-clock forms likewise

the subject matter of a special application Ser. #56,456 for U. S. patent, filed by me simultaneously with this application now Pat. 2,097,134.

In the accompanying drawing which forms part 5 of this specification I have represented an exemplification of a construction of the master-clock, which forms part of my present invention, Fig. 1 being a front-view of my present master-clock 10 including a contact-device serving to operate the secondary-clocks by supplying proper current-impulses thereto, and Fig. 2 a top-view of the clockwork of the master-clock shown in Fig. 1, said clockwork being developed out into a plane.

Referring more particularly to the drawing, the 15 gear-wheel 2 for the minute-hand is mounted to rotate with proper friction about the axle of the minute-wheel of the clockwork, said wheel 2 meshing with the change-wheel 3 mounted rotatably in the bearing-bracket 4 fast on the plate 1 of the clockwork. Mounted on the axle of said change-wheel 3 is the wheel 5 meshing with the pinion 6 of the lifting-wheel 1 carrying the lifting-pins 8. The wheel 7 is mounted rotatably between said plate 1 and a bearing-bracket 9 fast 20 on said plate. A pivot 10 is fastened to the plate 1 (Fig. 1) and a cranked lever 11, 12 is mounted swingably about said pivot 10. The free end of the horizontally directed arm 12 of said cranked lever carries a small weight 13. A further 25 cranked lever 15, 16 is swingably mounted on another pivot 14 on the plate 1, the cranked lever 15, 16 being arranged with respect to said former cranked lever 11, 12 in such a manner that said weight 13 rests on the free end of the horizontally directed arm 15 of said cranked lever 15, 16. The cranked lever 15, 16 is kept under the action 30 of a spring 17 tending to press the horizontal arm 15 against a pin 18 fixed to the plate 1. The contact levers 23, 25 together with the actuating 35 lever 20 are mounted swingably about a further pivot 19 fast on the plate 1. The actuating lever 20 carries on its free end a pin 21 by means of which said lever 20 rests on the vertical arm 16 that forms part of the cranked lever 15, 16. A 40 spring 22 exerts a constant downward pull on said actuating lever 20. The contact springs 24 and 26 are mounted on the contact levers 23 and 25, respectively, while the actuating lever 20 is equipped with a nose 27 upwardly extending 45 therefrom. The prolonged portion of the shaft of the main driving worm-wheel 28 carries the driving wheel 29 for the contact-device which serves to furnish the current impulses for the 50 operation of the secondary clocks.

On a further pivot 30 fast on the plate 1 is rotatably mounted the contact-wheel 32, a bushing 31 being interposed between said pivot and said contact-wheel. A sleeve of insulating material is placed on said bushing 31, said sleeve carrying a contact-cylinder 33 provided with a recessed part or incision 34, while a contact-pin 35 is mounted on the outer surface of said cylinder 33. The contact-wheel 32 is in mesh with the driving-wheel 29. The worm 38 coupled to the 55 shaft 36 of the small electric motor 37 is in mesh with the main driving wormwheel 28, the pinion 49 on the latter being in mesh with the wheel 39, the pinion 40 of the latter with the wheel 41 and the latter with the spring-barrel wheel 42. The minute-wheel 43 meshes with the pinion 44 60 on the wheel 45 which forms part of the driving work, said wheel 45 is again meshing with the pinion 46 of the ratchet-wheel 47 engaged by the pawl 48 forming part of the anchor-escapement.

The wheel 39 of the driving work meshes with

the wheel 50 (Fig. 1), the shaft 51 of the latter being provided with a sleeve of insulating material, said sleeve carrying the contact-disk 52 furnishing the current-impulses for operating the secondary clocks. The contact-disk 52 carries the contact-pin 53 and the two insulating pins 54 and 55. A contact-bolt 57 is mounted within a sleeve 56 of insulating material fast on the plate 1, a current-supply spring 58 being provided on said bolt 57, the free end of said spring sliding 10 on the periphery of said contact-disk 52.

On the plate 1 is further mounted an insulating plate 59, the terminals or binding-posts 60, 61, 62, 63 and 64 being fixed to said plate 59. Mounted rotatably about the binding-posts 60 and 61 15 is the contact-lever 65 and the contact-lever 66, respectively, while the binding-post 62 is provided at its upper end with an extension carrying the contact-plate 67. The contact-levers 68 and 69 are mounted rotatably about the binding-posts 20 63 and 64, respectively. The free upper ends of the contact-levers 66 and 68 are provided with rollers of insulating material and kept together by action of a tension-spring 70. In like manner also the upper ends of the contact-levers 65 and 69 are provided with rollers of insulating material 25 and kept together by a tension-spring.

The contact-bolt 57 is connected by way of the lead 71 to the one pole of the battery 72, the other pole of said battery being connected to the 30 binding-post 62 by way of the lead 73. Connected to the binding-posts 61 and 63 are the leads 74 and 75, the secondary clocks being interposed in parallel therebetween. The binding-post 60 is connected by the lead 77 with the one electrode of the coherer-resistance 78, the other electrode of the latter being connected with said lead 74 by the lead 79. Connected to the binding-post 64 is the lead 80 making connection with the one electrode of the coherer-resistance 81, the other 40 lead 75 by way of the lead 82.

On the plate 1 of the clockwork there is further mounted a binding-post 84 connected by a lead 85 with the one pole of a battery 86. The 45 other pole of said battery is connected by way of the lead 87 with the insulated binding-post 88, the latter making connection with one of the brushes of the small electric motor 37; the other of the brushes of said motor 37 is connected to 50 the binding-post 89 and the latter to the contact-bolt 91 by means of the lead 90, said contact-bolt 91 being provided with a spring 92 for supplying current thereto, said spring 92 sliding on the peripheral surface of the contact-drum 33 55 and being further provided with a contact-pin 93. The hour-wheel 95 forming part of the train of wheels for the hands of the clock is mounted rotatably on the bushing 96 of the minute-wheel shaft forming part of said train of 60 wheels for the hands of the clock and meshes with the pinion 57 of the change-wheel 3. On an arm 94 projecting from the running-wheel 29 there is provided a pin 98 at such a position with respect to the nose 27 on the aforesaid actuating-lever 20 that said arm 94 may co-operate 65 with said lever 20.

A coupling-disk 99 engages laterally with the driving worm-wheel 28, said coupling-disk being carried with said worm-wheel by action of friction therebetween.

The above described system of master-clock and secondary clocks operates as follows:

Upon clockwise rotation of the minute-wheel 2 forming part of the train of wheels for the 75

hands of the clock, the change-wheel 3 meshing with said minute-wheel 2 will be rotated counter-clockwise so that the wheel 5 mounted on the shaft of said change-wheel 3 will likewise be rotated. By way of the pinion 6 meshing with the wheel 5 also the wheel 7 carrying the lifting-pins 8 will be rotated in clockwise sense. Upon continued rotation of the wheel 7 the arm 11 connected to the weighted lever 12, 13 is gradually lifted by action of said lifting-pins 8, until said arm gradually slides off the respective lifting-pin. The arm 12 with the weight 13 thereon is thus likewise lifted at first together with said arm 11 and thereupon falls back, so that said weight 13 will rock the arm 15 of the cranked lever 15, 16 in downward direction. During the rocking motion thus imparted to the cranked lever 15, 16 about its pivot 14 the arm 16 will turn out towards the left, so that the pin 21 which had so far been resting on said arm will slide off the latter and now abut against the right-hand side thereof. By action of the spring 22 a powerful motion in downward direction is imparted to the actuating lever 20 swinging about the pivot 19, thus effecting proper displacement of the contact-levers 23 and 25, with the result that the contact-spring 24 will firmly abut against the contact-pin 93 and the contact-lever 23 against the contact-cylinder 33. The point of action of the spring 22 on the actuating lever 20 is properly located with respect to its center of rotation, that is with respect to the pivot 19, to effect a strong pressure between the contacting surfaces and therewith a reliable electrical contact for the control of the secondary clocks, as only a small adhesion between the pin 21 and the arm 16 of the cranked lever 15, 16 has to be overcome in the present case. By action of the contacts 23-33 and 24-93 an electric circuit 84-85-86-87-88-89-90-91-92-33-23 will be closed to operate the motor 37, 23-33 representing a sliding contact and 24-93 a point-contact, the latter coming into action with a small displacement with respect to the former. Closing of the circuit for the operating current is thus accomplished in a double way and in addition to this an automatic cleaning or polishing of the cooperating contact-surfaces attained. The small motor 37 will start immediately upon being inserted into circuit, thus imparting rotation by way of its shaft 36, the worm 38 thereon and the driving worm-wheel 28 meshing with said worm 38. Rotation is thus imparted to the running-wheel 29 which is mounted on the shaft of said worm-wheel 28 together with the pin 98 on the arm 94 projecting from said wheel 29. The running wheel meshes with the contact-wheel or disk 32 and likewise imparts rotation to the latter as well as to the contact-drum 33 mounted on the said contact-wheel or disk 32 and insulated therefrom. Upon continued rotation the pin 35 on the contact-drum 33 will abut against the contact-lever 23 and press the latter away from said contact-drum into initial position. Simultaneously therewith the actuating arm 20 is again lifted backward until the pin 21 on said arm 20 slides along the arm 16 forming part of the cranked locking lever 15, 16 and comes again in engagement with the latter, subsequent to the returning of said lever 15, 16 into its initial position abutting against the stop 18, by action of the spring 17. The motor 37, in spite of this, will continue to rotate, the contact-arm 25 still maintaining the motor circuit closed by action of the contact-spring 26. This circuit remains

closed until the contact-spring 26 comes out of contact with the contact-drum 33 when dropping into the recess 34 thereof. In the meanwhile the pin 35 on the contact-drum 33, upon further rotation, has come out of the range of action of the contact-lever 23. The motor 37 operating at no-load is thereupon caused to come to standstill by action of the pin 98 on the arm 94 projecting from the running wheel 29, said pin 98 engaging with the nose 27 on the actuating lever 20. During operation of the motor 37 the contact-wheels as well as the winding-wheels have simultaneously been set into rotation, re-winding of the driving-spring for the driving-wheels of the clockwork having been accomplished by way of the wheels and pinions 28, 49, 39, 48, 41 and 42. Re-winding of said spring is effected every minute, the amount of such re-winding being sufficient to keep the clock in operation until the next winding-up period.

The running gear-wheel 39 is also in mesh with the gear-wheel 50 for the contact-disk 52 insulated from its shaft, so that said gear-wheel 50 will be rotated through one half-revolution during every period of contact. By this the contact-pin 53 on said contact-disk 52 will close and open, alternately with one and the other of the contact-levers 66 and 68, the circuit which serves for the control of the secondary clocks 76. The direction of the current in this case changes as follows:

During the first contact-period the contact-pin 53 makes contact with the lever 68, thus closing the circuit 53, 68, 63, 75, 76, 74, 61, 66, 67, 62, 73, 72, 71, 57, 58, 52; during the second contact period the circuit 53, 66, 61, 74, 76, 75, 63, 68, 67, 62, 73, 72, 71, 57, 58, 52 will be established. In either case the insulating pins 54 and 55 on the contact-disk 52 will interrupt the contacts 66-67 as well as 67-68, before the contact-pin 53 comes in engagement with the levers 66 and 68, for the purpose of preventing a short-circuit from arising prior to proper closing of the circuit. The two auxiliary contact-levers 65 and 69 serve for the suppression of sparks eventually arising at the main-contacts. Said two contact-levers 65 and 69 during every contact-period are operated first, thus inserting into circuit in front of either main-lever one of the coherer-resistances 78 and 81, while during interruption of the circuit the levers 65 and 69 are subsequently separated from the contact-pin 53, so that in this case also the inserted coherer-resistance will come into action between the main and auxiliary contact.

I claim:

1. In a switch mechanism for master clocks and the like and which is operable by means of a small actuating force, the combination of a relatively fixed contact, a pivoted bell crank lever, a movable contact carried by one arm of said bell crank lever and cooperable with said fixed contact for completing an electrical circuit, resilient means for moving said bell crank in a direction to close said contacts, a latch for holding said bell crank against movement by said resilient means, a weighted element, means for periodically raising said weighted element and releasing it for relatively free falling movement, means for receiving impact of falling movement of said weighted element and transmitting the energy therefrom to said latch to move the latter to releasing position, whereby said bell crank lever may move to contact closing position, and means

for moving said bell crank lever to contact opening position.

2. In a switch mechanism for master clocks and the like, the combination of a relatively fixed contact, a pivoted lever, a contact carried by one arm of said lever and cooperable with said fixed contact, resilient means for moving said lever to contact closing position, a latch for holding said lever against movement by said means, a driving means capable of transmitting relatively small

forces, means to store up energy from said driving means and to release the stored energy suddenly, means to transmit the energy from said energy storing means to said latch to move the latter to releasing position, thereby permitting 5 said lever to move to contact closing position, and means to restore said lever to a position in which said contacts are open.

FERDINAND SCHNEIDER. 10
